UNITED STATES PATENT OFFICE.

LLOYD M. KNOLL, OF PHILADELPHIA, PENNSYLVANIA, ASSIGNOR OF ONE-FOURTH TO
THOMAS APPLEBY, OF PHILADELPHIA, PENNSYLVANIA.

RADIO SYSTEM.

REISSUED

1,394,026.

Specification of Letters Patent.

Patented Oct. 18, 1921.

Application filed April 2, 1920. Serial No. 370,683.

To all whom it may concern:

Be it known that I, LLOYD M. KNOLL, a citizen of the United States, residing in the city and county of Philadelphia, State of Pennsylvania, have invented new and useful improvements in Radio Systems, of which the following is a specification.

My invention relates to radio signaling or control systems involving the transmission through the natural media of electro-radiant energy or electromagnetic waves for telegraphy, telephony or other signaling or control purposes.

My invention resides in apparatus for the reception of electro-radiant energy from selected sources with a minimum of interference from other sources.

My invention further resides in apparatus for directional determination of electro-radiant energy sources.

My invention still further resides in combined uniform directional and non-uniform directional radio absorption structure and apparatus wherein the characteristics of both may be combined in a highly efficient and effective manner with a minimum of apparatus and adjustments.

My invention also resides in apparatus hereinafter described and claimed.

Heretofore whenever it was necessary or desirable to receive radio signals from certain specific transmitting stations, or for the purpose of ascertaining their direction, it has been customary to employ absorption structure of the so called "loop" or "exploring coil" type. The directional characteristics of these loops or coils are such that it is impossible to differentiate between the true and converse directions, both being indicated with equal facility, leaving much doubt as to which of them indicates the direction desired.

The structure of my invention eliminates all such doubt as it indicates only the actual direction of the transmitting station and reduces or annuls the effect of transmitters located in the opposite or other directions.

For an illustration of some of the forms my structure may take, reference is to be had to the accompanying drawing in which:

Figure 1 diagrammatically shows a radio receiving system embodying my structure.

Fig. 2 graphically indicates the directional characteristic of the structure herein described.

Fig. 3 is a modification of Fig. 1 in which a multiple of non-uniform directional structure are employed.

In Fig. 1 an ordinary radio antenna 1, of substantially uniform directional characteristic is connected to a counter-capacity or earth 2 through loop 3 and the primary coil 4 of radio frequency transformer 5. Shunted around the primary coil is a variable tuning condenser 6^a which may also be connected so as to shunt both the primary coil and the loop as shown in Fig. 3. The arrangement thus far described constitutes the absorption, primary, or antenna circuit.

Loop 3 consists of a rectangular, flat helical, round, or other suitably shaped coil, wound on a frame or any other suitable means of support rotatively mounted on its vertical axis and of such dimensions and convolutions of conductor that it will absorb energy from passing electromagnetic waves with fair proportion to that of antenna 1.

As well known in the art an ordinary antenna, especially if of the vertical type, itself absorbs energy equally well from all directions and therefore has a substantially uniform directional characteristic, which, in refined cases, may be graphically represented by a circle, as at A, Fig. 2.

Loop 3, of the type described, when used alone absorbs most energy when the plane of its winding is in the line of wave propagation or at right angles to the wave front. The non-uniform directional characteristic of such a loop is commonly called a "figure eight", which it resembles, as indicated graphically by the two circles B and B' in Fig. 2.

The energy absorbed by and flowing in the loop is said to be due to phase difference between its sides; the momentary flow of energy absorbed by the antenna may be in the same or the opposite direction to that flowing in the side of the loop to which the antenna is connected, depending upon the direction of the transmitting station and the position of the loop.

When passing electromagnetic waves act on antenna 1 and the loop 3 a current is pro-

duced in each of them and these currents act simultaneously (for example by induction, as in the case illustrated) on the detector 11. The resultant action on the detector differs from that which would be produced by the antenna or the loop acting separately. If the action, on the detector, of the antenna and the loop are equal and in phase the maximum effect will be produced 10 in the head-telephones 14; if the said actions are equal but opposite the minimum effect will be produced.

By connecting the absorbing loop directly in the antenna circuit I prevent any 15 harmful distortion of their resultant directional characteristic such as may occur if the antenna alone were in the antenna circuit and the loop in the secondary circuit and the two inductively coupled by a variable-coupling transformer.

Secondary coil 6 of transformer 5 is shunted by a tuning condenser 7 and connected in any conventional manner to a detector of any type. In the case illustrated a detector of the 25 vacuum tube or electron discharge type is shown, comprising an anode or plate electrode 8, grid 9, and filament 10, all inclosed in evacuated envelop 11. Energy for heating the filament and thus causing it to emit 30 electrons is supplied by a battery or any other convenient source 12 through a regulating resistance 13. One terminal of head-telephone receivers or other suitable translating device 14 is connected to the plate electrode 8 and the other terminal to the positive side of battery 15, or its equivalent. A variable condenser 16 is shunted across the head-telephones and battery 15 for the purpose of by-passing radio frequency currents 35 in the plate circuit. A grid condenser 17 is connected in series with the grid. The connections thus shown comprise one form of regenerative or oscillation generating circuit and may be used for the reception of damped 40 or undamped waves. It will also be understood that any number of vacuum tubes may be added for the purpose of amplifying the received energy.

Fig. 2 illustrates at A, B, B' and C the 50 effects of the antenna and the loop and of the resultant effect on the detector. The resultant curve C is obtained by taking the effect on the detector of the uniform absorption of the antenna as equal and in phase 55 with the effect on the detector of the loop illustrated by the circle B, and as equal and opposed in phase on the detector of the loop illustrated by the circle B'. The points from which curve C is plotted will consequently be obtained by adding to the uniform radii of A which traverse B the corresponding vector radii of B, and by subtracting from the uniform radii of A which traverse B' the corresponding vector radii of B'. 60

It will be readily understood that the fre-

quency constants of antenna 1 will to a certain extent limit the inductance of coil 3 for any given wave-length, and the energy absorbed by the antenna and the coil will be considerably limited if they are so proportioned that their absorption factors are substantially equal. In order to increase the size of the antenna and absorb greater energy, yet at the same time keeping the absorption due to the non-uniform absorption 70 structure in proper proportion, a second coil 75 3^a has been added in the secondary circuit as shown in Fig. 3 which comprises a modification of Fig. 1. The two parallel loops or coils 3 and 3^a are wound on frames or 80 other suitable means of support and sufficiently separated that their respective fields have little or no effect upon each other. The frames are secured to a bar 18 to which is attached a vertical shaft 19 rotatively 85 mounted in bearings 20 and 21 of supporting base 22. The upper end of base 22 comprises a compass scale and by means of a pointer 23 secured to shaft 19 the angular bearings of intercepted stations may be readily determined.

The primary coil 4 and secondary coil 6 of transformer 5 are so arranged that they may be rotated relative to each other or separated any suitable distance to reduce the 95 electromagnetic coupling between them which reduces the energy transferred from the primary to the secondary circuit and the detector. Such an arrangement is very useful especially when strong signals are 100 being received in order that more accurate or closer directional reading may be obtained.

What I claim is:

1. A unilateral directive radio system comprising an antenna circuit containing uniform and non-uniform directional absorption structure serially connected. 105

2. A directional radio system comprising a primary circuit containing uniform and 110 non-uniform directional absorption structure, and a secondary circuit containing non-uniform directional absorption structure.

3. The combination of a primary absorption circuit containing uniform and non-uniform directional absorption structure and a primary coupling coil all serially connected, and a secondary circuit containing a secondary coupling coil and a translating device. 115

4. The combination of a primary absorption circuit containing uniform and non-uniform directional absorption structure, and a primary coupling coil; and a secondary circuit containing non-uniform directional 125 absorption structure, a secondary coupling coil, and a translating device.

5. A unilateral directive radio absorption circuit comprising absorption structure having a substantially uniform directional char- 130

- acteristic serially connected to absorption structure having a substantially non-uniform directional characteristic.
6. A unilateral directive radio absorption circuit comprising absorption structure having a substantially uniform directional characteristic serially connected to absorption structure having a substantially non-uniform directional characteristic, the currents of said absorption structures having substantially equal amplitudes.
7. A unilateral directive antenna circuit comprising a plain antenna and an absorption coil serially connected, and means for varying the phase relation of the currents of said absorption coil with respect to the currents of said antenna.
8. A unilateral directive antenna circuit comprising an antenna and an absorption coil serially connected, and means for varying the phase relation and amplitude of the currents of said absorption coil with respect to the currents of said antenna.
9. The combination in a unilateral radio system of a plain antenna and an absorption coil serially connected, and means for varying the phase relation and amplitude of the currents of said absorption coil with respect to the currents of said antenna.
10. A unilateral directive radio signaling system comprising in combination a plain antenna and a directive loop serially connected to earth, and means for varying the phase relation and amplitude of the currents in said loop with respect to the currents in said antenna.
11. A unilateral directive radio signaling system comprising absorption structure having a substantially uniform directional characteristic serially connected to a counter-capacity through a rotatable absorption structure having a substantially non-uniform directional characteristic.
12. In a unilateral directive radio system, the combination with a plain antenna of a directive loop and a counter-capacity all serially connected.
13. A unilateral directive antenna circuit comprising a plain antenna, a directive loop, and a counter-capacity all serially connected, and means for producing in said antenna circuit currents of different phase.
14. A unilateral directive antenna circuit comprising two absorption structures, one having a non-uniform directional characteristic, and a counter-capacity all serially connected and means for producing in said antenna circuit currents of different phase.
15. A unilateral directive antenna circuit comprising two absorption structures, one having a non-uniform directional characteristic, and a counter-capacity all serially connected and means for producing in said antenna circuits currents of different phase and amplitude.
16. A radio signaling system comprising a primary circuit containing uniform and non-uniform directional antenna structure, a secondary circuit containing non-uniform directional antenna structure, and means for coupling said primary circuit to said secondary circuit.
17. A radio signaling system comprising a primary circuit containing uniform and non-uniform directional antenna structure, a secondary circuit containing non-uniform directional antenna structure, and means for inductively coupling said primary circuit to said secondary circuit.
18. A directive radio signaling system comprising a primary circuit containing a non-directional antenna and a rotatable loop; a secondary circuit containing a rotatable loop, and means for coupling said primary circuit to said secondary circuit.
19. A directive radio signaling system comprising a primary circuit containing an antenna and a rotatable coil; a secondary circuit containing a rotatable coil, and means for inductively coupling said primary circuit to said secondary circuit.
- In testimony whereof I have hereunto affixed my signature this 31st day of March, 1920.

LLOYD M. KNOLL.
